PAGE 3

FIG. 3

FIG. 4

FIG. 5

FIG. 6

FIG. 7

FIGURE 1 is a front and left side perspective view of a photoelectrostatic reprographer showing our new design;

FIGURE 2 is a front and right side perspective view thereof;

FIGURE 3 is a front elevational view thereof;

FIGURE 4 is a top plan view thereof;

FIGURE 5 is a left side elevational view thereof;

FIGURE 6 is a right side elevational view thereof; and

FIGURE 7 is a rear elevational view thereof.

We claim:

The ornamental design for a photoelectrostatic reprographer, as shown.
